SOUND RECORDING AND REPRODUCING
MACHINEJacob Miles Kuhlik, Brooklyn, N. Y., assignor to
Hattie B. Kuhlik, Brooklyn, N. Y.Original application June 14, 1940, Serial No.
340,447. Divided and this application July 4,
1942, Serial No. 449,710

7 Claims. (Cl. 274—11)

1

This invention relates to sound recording and reproducing machines having a strip of film and is a division of my application Serial Number 340,447, filed June 14, 1940.

A primary object of my invention is to provide such a machine that is simple and inexpensive to manufacture and compact in structure.

Another object is to provide such a machine with means for driving its strip of film without the need of sprocket wheels for engaging perforations in the film.

Another object is to provide such a machine with visible means for indicating the position of the stylus transversely of the film when recording.

Another object is to provide such a machine with separate visible means for indicating the position of the stylus transversely of the film when said stylus is retracing a line or track previously cut by the stylus.

Another object is to provide visible means for indicating the location of the stylus longitudinally of the film.

Still another object is to provide means for readily rewinding the film.

Another object is to provide means for positioning the stylus on any desired track on the film.

Another object is to provide means for adjusting the pressure of the stylus on the film for recording or reproducing purposes.

Another object is to provide means for automatically stopping the movement of the film.

Another object is to provide such a machine with an imperforate strip of film thereby preventing the weakening of such strip along its edges by perforations and preventing the necessity of sprocket drive wheels.

The foregoing and other objects and advantages of my invention will be better understood from the description thereof to follow taken in connection with the accompanying drawings in which—

Fig. 1 is a front view of a sound recording and reproducing machine embodying my invention, parts being shown in section and parts being shown removed for the sake of clearness.

Fig. 2 is a top plan view of the machine of Fig. 1 with the top or cover of the casing removed.

Fig. 3 is a view thereof with the wall of the casing removed, with some of the parts in section and some shown in dotted lines.

Fig. 4 is a fragmentary detail view showing the main drive shaft and associated parts.

Fig. 5 is a fragmentary detail view showing the recording and reproducing head and mechanism for adjusting the pressure of the stylus on the film.

Fig. 6 is an enlarged fragmentary detail view of a bell crank and associated parts for actuating the clutch slide.

2

Fig. 7 is a detail view showing the mechanism for indicating the position of the stylus transversely of the film when retracing a line previously cut by the stylus.

Fig. 8 is an enlarged detail view of the actuating mechanism for the clutch device on the main drive shaft.

Fig. 9 is an enlarged detail view of the mechanism for moving the recording and reproducing head transversely of the film with modified means for permitting free movement of the said head along its mounting shaft.

Fig. 10 is a detail view of the mechanism of Fig. 9 looking from the left.

Fig. 11 is an enlarged detail view of the mechanism for holding the recording and reproducing head and stylus in adjusted position.

Fig. 12 is an enlarged fragmentary detail view of the mechanism for visibly indicating the position of the stylus transversely of the film when recording.

The improved machine as shown is of the portable type and may be housed in a box like casing 100 having a hinged front door 101 and a hinged cover lid portion 102. The casing is provided with a rear wall or panel 2b, an intermediate wall or panel 2a spaced forwardly thereof and a front panel 2c extending downwardly from the top of the casing to a point just above the middle thereof. The panels 2a and 2b are supported on a base 3a on the bottom wall of the casing, and these panels support the various mechanisms of the machine.

Rotatably mounted in suitable bearings in supporting walls 2a and 2b at one side of the casing is a shaft or spindle 103 and removably mounted on the outer end thereof is a supply reel 31a, and rotatably supported in similar fashion on the other side is a shaft or spindle 104 for removably mounting a receiving or take-up reel 26a. A strip of film 105 is carried by the supply reel 31a and is adapted to be taken up by the receiving reel 26a. This film is of a width as ordinarily used in such machines and may for example be 500 feet long or any desired length. It is however without any perforations on the side edges as is customary. It passes in its forward movement from the supply reel 31a upwardly and over a flanged roller 200 supported on a stud on the wall 2a and over a guide block or base 281 supported on the wall 2a above the roller 200. From the base 281 the film passes forwardly over a rubber-faced pressure drive roller 203 and then rearwardly over a pressure roller 204 mounted on a stud on the front of wall 2a below and rearwardly of the roller 203 in the direction of the travel of the film and from the roller 204 it travels to and over the receiving reel 26a.

A head member 202, containing electromagnetic means for converting varying electrical

currents into mechanical movements of the stylus or for converting movement or vibrations of the stylus into corresponding electrical currents as is well understood, is so mounted adjacent the base 201 that it will move across the film during its forward travel from the supply reel 31a to the receiving reel 26a. This head carries the usual stylus 202 provided with a recording point which is adapted to cut a groove in the film as the film is moved past the same in its forward travel. This head is adapted to be moved transversely to the motion of the film in graduated steps in order that a large number of closely spaced grooves or lines may be recorded on a single strip of film. Movement of the stylus is controlled by the mechanism included in the head 202.

The mechanism for moving the film along its path includes a motor M bolted to the rear of the supporting wall 2b and which is suitably connected to a source of electro motive force (not shown). The motor frame is provided with an extension frame 107 and supported in said frame and operatively connected to the motor shaft is a governor device 108 and mounted on the motor shaft between the motor and governor is a brake disk 109.

Operatively connected to the motor shaft is a shaft or spindle 206 which is supported by a bearing member 207 in the wall 2b and extends forwardly to a point near the forward wall 2a. Supported in alignment with shaft 206, in an elongated conical shaped bearing member 208 in the wall 2a, is a driven shaft or spindle 209, the inner end of which is positioned close to the outer end of shaft 206 and is slotted as indicated at 209'. A disk or collar 210 is fastened to the outer end of a sleeve member 211 which is slidably mounted on the outer end of the shaft 206. The sleeve 211 is formed with opposite elongated slots for cooperating with a pin 211' fastened to and protruding through shaft 206 by which the sleeve is rotated with the shaft 206 but is permitted to slide along it. A clutch pin 212 is carried by the collar 210 and extends through and across the slidable sleeve 211 for coaction with the edge walls of the slot 209' in shaft 209, for operatively connecting the shafts 206 and 209.

Slidably and loosely mounted on the shaft 206, adjacent the inner end of the sleeve is a sprocket wheel 213 having a grooved hub portion with a pin 214 extending outwardly therefrom and parallel to the shaft 206. A pin 215 protrudes on both sides of the shaft 206 at a point adjacent said sprocket wheel 213 in a position to be engaged by the pin 214 in order to carry the wheel around with the shaft 206.

And slidably and loosely mounted on the shaft 206 adjacent said pin 215 is a grooved pulley 217 having a pin 218 protruding from its face toward the pin 215 and adapted to be moved into engagement with said pin to operatively connect the pulley with the shaft 206.

The mechanism for sliding these various devices into operative connection with the shaft 206 includes a sliding carriage 220 slidably mounted on a rod 221 fastened to walls 2a and 2b. Depending from the carriage at its end adjacent wall 2a is a forked arm 220', the fork portions of which straddle collar 210. Midway the length of the carriage an arm 220" is fastened thereto and depends therefrom and protrudes into the groove in the hub of socket wheel 213. On the other end of the carriage is another forked arm 220x, the forked portions of

which straddle the pulley 217. By reason of this construction, when the carriage 220 moves, the collar, sprocket wheel and pulley move simultaneously with it. These parts are shown in neutral position in Fig. 8. When the carriage is moved to the left as shown in Fig. 4 the collar 210 with its clutch pin 212 is moved away from driven shaft 209 and the shaft 209 is disconnected from the drive shaft 206. At the same time, the sprocket wheel 213 is moved to bring its pin 214 into engagement with pin 215 on the shaft 206 so as to drive the wheel around with shaft 206. The pulley 217 with its pin 218 is simultaneously moved away from operative position with pin 215.

When the carriage is moved to the right, the collar is moved to bring its clutch pin 212 into the slot 209' in driven shaft 209 to connect it with shaft 206, and at the same time sprocket wheel 213 with its pin is moved out of engagement with pin 215, and the pulley 217 with its pin 218 is moved into engagement with said pin 215 in order to drive the pulley around with shaft 206.

The mechanism for moving the head 202 transversely of the film includes a bar or shaft 222 rotatably mounted in suitable bearings in walls 2a and 2c. This shaft is provided with external screw threads from its rear end to a point remote from the wall 2c. A carriage member 223 formed with a central opening with internal screw threads is mounted on said shaft so that the threads of said opening engage the threads on the shaft. Rotation of the shaft 222 will move the carriage with its head 202 along said shaft as will be understood.

The carriage 223 is so mounted on the shaft 222 that it is adapted to be swung in a vertical plane in order to relieve the pressure of the stylus upon the film, and the mechanism for this purpose is operatively connected to the mechanism for actuating the carriage for moving the collar 210, sprocket wheel 213 and pulley 217. It includes a flat spring bar or plate 224, one end of which is fastened to the top of the carriage 223 and the other end of which is free and extends outwardly of and away from said carriage, and is adapted to coact with said actuating mechanism as will be presently described.

The mechanism for actuating said carriage 220 consists of a shaft 225 journalled in bearings in the walls 2a and 2c near the top thereof and to one side of the casing 100 and disposed parallel to shaft 222. Fastened to the inner end of shaft 225, on the rear of the wall 2a, is an upstanding arm member 226. An elongated bar or lever member 227 has a pin and slot connection with arm 226 at one end and a pivotal connection with the short arm of a bell crank 228 pivotally supported by a bracket 229 which is secured to the wall 2a adjacent the head 202. The long arm of the bell crank is pivotally connected to one end of a lever arm 230, the other end of the lever 230 being connected to an upstanding post or stud 231 fastened to the carriage 220. Also fastened to the shaft 225 near its inner end but on the opposite or forward side of the wall 2a is an upstanding detent arm 233 having a tubular bearing portion or socket 233' formed at its upper end and disposed close to the front surface of wall 2a for receiving a spring pressed pin or plunger 233x, the protruding end of which is adapted to be pressed against the surface of said wall. The wall surface at this point is formed with spaced depressions 234 arranged in

an arc and adapted to receive the protruding end of the plunger to hold the arm 233 in adjusted position. A finger knob 235 provided with a pointer is secured to the outer end of shaft 225 for rotating said shaft. Secured to the shaft 225 adjacent the arm 233 is a disc member 236 provided with a U-shaped notch 237, the disc being so arranged relative to the carriage 223 on shaft 222 that the projecting free end of the spring bar 224 is positioned within the notch 237 as seen in Fig. 5. The end of the bar 224 is adapted to assume four different positions in the notch 237 which positions may be indicated by the letters "a," "b," "c" and "d" on a scale Z on the face of front panel 2c and arranged in an arc to conform to the swing of the pointer 235 as will be seen from Fig. 5. Instead of the letters here shown any desired descriptive or arbitrary indicia may be used as will be understood. The depressions 234 in plate 2a conform in number and spacing with the letters indicating the positions of the bar and head 202.

By turning the knob 235 on the outer end of the shaft 225 the slide carriage 220, through the interconnection between the upstanding arm 226 and stud 231, is adapted to be moved to the right or left as viewed in Figs. 3 and 4. When moved to the right to the position of Fig. 4, the drive shaft 208 driven by the motor and the driven shaft 209 are clutched together by the clutch pin 212 to rotate the drive feed roller 203 to move the film forward from supply reel 31a to receiving reel 26a as viewed in Fig. 1. The pulley 217 is shifted so that its pin 218 engages pin 215 on shaft 206 so as to drive said pulley and compensating spring belt 205 for driving the pulley 106, on shaft 104 and through it the receiving reel 26a. The spring belt 205 compensates for any difference in the speeds of the roller 203 and reel 26a. This is the position of the parts for moving the film forward for recording. When the parts are in this position, the disc 236 will have been moved around so that the lower edge of the wall of notch 237 will engage the free end of the flat spring bar 224 and lift the same upwardly to exert a maximum pressure on the head 202 and the stylus to supply the necessary pressure for making impressions or tracks upon the film for recording purposes. This is the recording position and is indicated on the scale Z as "a," but it may be indicated by the letter "R" for "recording" or any other suitable indicia might be used.

When the carriage 220 is moved to the left, the collar 210 with its clutch pin 212 is moved away from the drive shaft 209 and said shaft is disengaged from the drive shaft 206. At the same time, the pulley 217 with its pin 218 is moved away from the pin 215, and the sprocket wheel 213 with its pin 214 is shifted into engagement with the pin 215. In this position, the sprocket wheel 213 is rotated with shaft 206 and through the chain 216 rotates the wheel 107 on shaft 103 to rotate the supply reel 31a. This is the rewind position for moving the film from the receiving reel 26a to the supply reel 31a to rewind the film on to said supply reel. This rewind position is indicated on the scale Z as "d."

In moving the carriage to this rewind position, the shaft 225 is rocked and the disk 236 moved clockwise as shown in Fig. 5 so that the outer edge of the upper wall of notch 237 will have engaged the free end of the bar 224 and pressed the same downwardly to exert a pressure on the carriage on the left side of the shaft 222

as seen in Fig. 5 and thereby lift the head 202 and stylus free of the film thereby permitting the film to move freely from the take-up reel 26a to the supply reel 31a for rewinding. In this position of the parts the pointer will be pointing to "d" on the scale.

When the disc 236 is moved clockwise as seen in Fig. 5 so that the bottom of the notch 237 moves downwardly and the pointer points to "b" on the scale, while the spring bar 224 still touches the bottom wall of the notch, the pressure on said bar is relieved and consequently the pressure on the head 202 and its stylus so that only the dead weight of the head and carriage is exerted on the stylus sufficient to keep the stylus in position in the groove cut in the film and touching the walls thereof for reproducing or play-back. This is the reproducing or play-back position of the parts.

When the shaft is rocked so that the pointer of the knob turns to the position "c" on the scale, the walls of the notch 237 in disk 236 will have been moved free of the end of the spring bar 224 so that said end is positioned between the two walls. When the bar and disk are thus positioned, the carriage 223 may be swung slightly and the head and stylus lifted sufficiently to permit the stylus to be removed and replaced. This may be called the neutral position of the parts.

The parts may be moved to these various positions without moving the carriage 220 by reason of the lost motion connection between lever 227 and arm 226.

An important feature of my present invention is the means for indicating the position of the stylus transversely of the film when recording. This mechanism is shown in detail in Fig. 12 and includes the worm threads 238 formed on the shaft 222 adjacent its outer end, said outer end supporting a finger knob 235a for actuating the shaft and formed with a pointer. Spaced shafts 240 and 242 formed with cylindrical body portions or spools having radial sprockets at their bottom ends are rotatably mounted on brackets on the inner surface of front panel 2c. On the bottom end of shaft 240 is a worm gear 239 disposed so as to be in continuous mesh with the threads 238 of shaft 222 and adapted to be moved thereby. Supported on the cylindrical body portions and movable therearound by the sprockets thereon is an endless strip of tape 241 perforated at its bottom edge to engage the sprockets. This tape bears spaced numerals, for instance, from "1" to "40" to indicate the number of spaced tracks or grooves cut or capable of being cut on the film from edge to edge thereof. Rotation of the shaft 222 by the knob 235 one complete turn moves the head with its stylus one step or space along the shaft, and as the shaft is turned to so move the head one space the worm gear 239 moves the shaft to correspondingly move the endless tape one point or numeral to the front of the pointer. The first groove nearest one edge of the film is numbered "1" on the endless tape and the succeeding grooves are successively numbered on the tape as will be understood. A window 243 is formed in the front panel 2c in order to expose the tape so that the operator can see at a glance on which track or groove the stylus is positioned.

The mechanism for indicating the position of the stylus longitudinally of the film includes, in addition to the driven shaft 209 and drive roller 203, a sprocket device 244 carried by the roller 203. A chain 245 is driven by this sprocket 244

which in turn drives a sprocket wheel on a shaft 246, journaled in walls 2a and 2c, for turning said shaft. Fixed on said shaft adjacent the outer end thereof is a miter gear 247. Mounted on the inside of the panel 2c is a meter or counting device 248, which in the present case registers footage. This counting device is operatively connected to the gear 247 by a shaft 248' with a gear on its end meshing with said gear 247. The film 105 is suitably marked at spaced intervals therealong, with identification marks, for indicating the various spaces or zones therealong. For instance it may be marked at every foot of its length with a number, starting at one end thereof with the number "1" and numbering the spaces consecutively up to, for instance, "500" if the film is that long. Other identification marks may be used of course, such as, the letters of the alphabet. The counting device will of course be preset to correspond with the correct mark on the film so that the mark or number, for instance, as it passes under the stylus will be registered on the counting device. A window 249 is formed in the panel 2c for viewing the counting device in order to give the operator a chance to see what particular section or zone of the film is being operated upon by the stylus. This greatly facilitates the reproducing of the recorded matter on any particular zone or section desired.

It is often desirable to indicate the position of the stylus on the film transversely thereof independently of the indicating mechanism shown in Fig. 12 when the stylus is retracing a track or groove previously cut on the film. The means for accomplishing this is shown in detail in Fig. 7 and includes a bracket 250 on the inner surface of front panel 2c for pivotally supporting a movable pointer member 251. Supported on the wall 2a and panel 2c and extending therebetween is a fixed scale 252 bearing numbers from "0" to "40" to indicate the number of grooves cut on the film from edge to edge. It is so positioned that the pointer moves across its surface and points to said numerals, during its movement. The pointer is formed with a rear curved arm which is in engagement with the side wall of carriage 223 and held in such engaging position by a spring 253 so that as the carriage moves along the shaft 222 it forces the arm ahead of it which turns the pointer on its pivot to move its outer free end across the scale. For example, if the carriage with its head and stylus is manually moved to groove or track 8, the pointer will be moved and point to "5" on the scale.

Means are also provided for controlling the speed of the motor M. For this purpose a shaft 254 is journaled in walls 2a and 2b. On the inner end of the shaft is fastened a cam device 255 which is in operative engagement with a pivoted lever or arm 256 which is adapted to engage the braking disc 109 on the motor shaft to control the speed thereof. A finger knob 257 is mounted on the outer end of the shaft 254 to actuate the same.

An amplifier, the tubes only of which are shown diagrammatically at 258 in Fig. 3, and a loud speaker 259, mounted on panel 2c, are operatively connected to the recording and reproducing head as will be understood.

In Figs. 9 and 10, I have shown modified structure for permitting the recording and reproducing head, when recording on a particular track, to be moved over to another already impressed track or groove for the purpose of reproducing the recorded matter on said latter impressed

track and then subsequently to restore the head and stylus to its former position on the recording track. In this modified structure, the carriage 223 which carries the head 202 and stylus is provided with an opening for receiving shaft 222, which opening is free from internal threads to permit the carriage to move along the shaft 222 freely of the external threads thereon. Pivotedly secured to one side of the carriage however is an arm or lever member 222' which is provided with an internally screw threaded curved portion for engagement with the threads on the shaft. A curved spring 222a holds the arm in engagement with the shaft whereby the carriage moves along the shaft controlled by the engaging threads. When it is desired to move the head and stylus to a track previously impressed or cut, the pivotal arm 222' is manually moved off of the shaft so that the threads are disengaged to permit the carriage to move along the shaft freely. During this operation, the shaft 222 is motionless and the indicating tape 241 will therefore remain stationary to indicate the particular track where the stylus had been moved from.

The desired impressed track, the subject matter of which it is sought to play back or reproduce, is found by the mechanism shown in Fig. 7. The carriage 223 is adapted to move freely in either direction on the shaft 222 and during such movement forces the pivoted or movable pointer 251 along the scale. If it is desired to reproduce matter on track "15" for instance, the carriage is moved along the shaft to move pointer 251 to "15" on the scale. The arm 222' is then returned to the shaft 222 to hold the head on track "15." When the play-back has been finished on track "15," the head and stylus can be again moved along the shaft to the desired track indicated on the tape 241 in order to finish the recording on that particular track.

I claim:

1. In a recording and reproducing machine, a recording and reproducing head, a stylus operatively connected thereto and supported thereby, a traveling film adapted to be engaged by said stylus for cutting a groove thereon, a support for said head and stylus including a carriage movably mounted to position said stylus at a plurality of different transverse positions relative to the path of movement of said film, said carriage having a central opening, an externally screw threaded shaft extending freely through said opening and an arm member hingedly mounted on said carriage and having an arcuate-shaped internal screw threaded bearing portion adapted to be moved into engagement with the threads on said shaft for step by step movement of the carriage and adapted to be moved away from said shaft to permit the carriage to move freely on the shaft.

2. In a recording and reproducing machine, a recording and reproducing head, a stylus operatively connected thereto and supported thereby, a traveling film adapted to be engaged by said stylus for cutting a groove thereon, a support for said head and stylus including a carriage movably mounted to position said stylus at a plurality of different transverse positions relative to the path of movement of said film, said carriage having a central opening, an externally screw threaded shaft extending freely through said opening and means in common for selectively moving said carriage along said shaft in a controlled step by step movement and for moving said carriage freely along said shaft including

an arm member pivotally mounted on said carriage and having an internal screw threaded arcuate-shaped bearing portion adapted to be moved into engagement with the threads on said shaft for step by step movement of the carriage and adapted to be moved away from said shaft to permit the carriage to move freely on the shaft and a bowed spring on the carriage for urging said arm into engagement with the shaft.

3. In a recording and reproducing machine, the combination with a traveling film, a recording and reproducing head, a stylus supported by said head, a support for said head and stylus including a carriage movably mounted to position said stylus at a plurality of different transverse positions relative to the path of movement of the film for impressing a plurality of grooves on said film, means for moving said carriage including a manually actuated screw threaded shaft and means for indicating the position of the stylus transversely of the film including an endless tape having indicia thereon, rotatable members for movably supporting said endless tape, means for moving said rotatable members whereby said tape is moved a distance to correspond to the movement of the carriage including a worm and gear connection between said shaft and one of said rotatable members and a pointer on the end of said shaft for coaction with said indicia and independent means for indicating the position of the stylus transverse of the film when the stylus is retracing a track.

4. In a recording and reproducing machine, the combination with a traveling film, a recording and reproducing head, a stylus supported by said head, a support for said head and stylus including a carriage movably mounted to position said stylus at a plurality of different transverse positions relative to the path of movement of the film for impressing a plurality of grooves on said film, means for moving said carriage including a manually operated screw threaded shaft, means for indicating the position of the stylus transversely of the film when recording, means independent of said first named indicating means for positioning the stylus in any selected groove, said positioning means including a scale having spaced numbers corresponding to the grooves on the film, a pivoted pointer having a portion movable over said scale and a portion in engagement with said carriage and movable therewith for moving the pointer a distance over the scale equal to the distance moved by the carriage and means for holding the carriage in adjusted position including a pivoted arm carried by said carriage and a spring for holding said pivoted arm in engagement with the shaft.

5. In a recording and reproducing machine, a traveling film, a recording and reproducing head, a stylus operatively connected to and supported by said head, a support for said head and stylus comprising a carriage movably mounted to position said stylus at a plurality of different transverse positions relative to the path of movement of the film for impressing a plurality of spaced grooves in said film, and mechanism for adjusting the pressure of said stylus on said film including a spring bar having one end secured to said carriage and having its other end extending freely outwardly therefrom, a disk rotatably supported adjacent the free end of said spring bar, said disk having a notch formed in its periphery and adapted to receive the free end of said spring bar and means for rotating said disk whereby the

walls of said notch are adapted to engage the free end of said spring bar for moving the head toward and away from the film to adjust the pressure of the stylus thereon.

6. In a recording and reproducing machine, a traveling film, a recording and reproducing head, a stylus operatively connected to and supported by said head, a support for said head and stylus comprising a carriage movably mounted to position said stylus at a plurality of different transverse positions relative to the path of movement of the film for impressing a plurality of spaced grooves on said film, mechanism for adjusting the pressure of said stylus on said film including a spring bar having one end secured to said carriage and having its other end extending freely outwardly therefrom, a disk rotatably supported adjacent the free end of said spring bar, said disk having a notch formed in its periphery and adapted to receive the free end of said spring bar, means for rotating said disk whereby the walls of said notch are adapted to engage the free end of said spring bar for moving the head toward and away from the film to adjust the pressure of the stylus thereon and means for holding the head in adjusted position.

7. In a recording and reproducing machine, a casing, a traveling film, a recording and reproducing head, a stylus operatively connected to and supported by said head, a support for said head and stylus comprising a carriage movably mounted to position said stylus at a plurality of different transverse positions relative to the path of movement of the film for impressing a plurality of spaced grooves on said film, a rockable shaft supported by a wall of said casing, means for rocking said shaft, mechanism for adjusting the pressure of said stylus on said film including a spring bar having one end secured to said carriage and having its other end extending freely outwardly therefrom, a disk fastened to said rockable shaft, said disk having a notch formed in its periphery and adapted to receive the free end of said spring bar whereby the walls thereof are adapted to engage said end of the bar for moving the head toward or away from the film to adjust the pressure of the stylus thereupon and means for holding the head in adjusted position including an upstanding arm on said rockable shaft adjacent a fixed portion of said casing wall, said wall portion having spaced depressions and a spring pressed pin supported on the end of said upstanding arm for engaging in said depressions to hold the disk against movement.

JACOB MILES KUHLIK.
